UNITED STATES PATENT OFFICE.

VICTORINO MARTINEZ, OF HABANA, CUBA.

INCANDESCENT ELECTRIC LAMP.

1,283,848.

Specification of Letters Patent.

Patented Nov. 5, 1918.

Application filed June 4, 1917. Serial No. 172,776.

To all whom it may concern:

Be it known that I, VICTORINO MARTINEZ, a citizen of the Republic of Cuba, and a resident of Habana, Cuba, have invented 5 certain new and useful Improvements in Incandescent Electric Lamps, of which the following is a specification.

This invention relates to incandescent electric lamps, particularly to those electric 10 lamps used in connection with non-metallic sockets, such as the socket described and illustrated in the specification and drawings of an invention of the applicant which is entitled "Improvements in electric lamp 15 holders," an application for which was filed April 15th, 1916, U. S. Serial No. 91469, and is now Pat. No. 1,226,558. Its object is to provide a new lamp not provided with the metallic casket that the lamps heretofore 20 used have, but the only metallic part which it has is that of the two contacts required for the passage of the electric current to the filament, this new lamp being advantageous for the reason that its cost of manufacture 25 is cheaper than that of the lamps at present in use.

The invention is described with reference to the figures of the annexed drawing, of which:

30 Figure 1 is an outer elevation of a lamp provided with the improvements which are the object of this invention.

Fig. 2 is an upper plan view thereof.

35 Fig. 3 is a diametral vertical section of same.

And Fig. 4 is an outer elevation of said lamp in connection with a proper socket, this one being shown in section.

The lamp 1 which is the object of this 40 invention is without a metallic casket and its glass collar 2 is provided with a screw thread 3 for its securing to the socket or lamp holder, and its upper portion, that is the part on which the glass is bent inwardly 45 and downwardly for securing or holding the metallic conductors 4 and 5 constituting the electrodes, forms on its inner face an annular setting 6 which is designed to receive a metallic ring 7 which is preferably 50 provided with projecting inner points 8 in number of four or more equidistant between one another and which constitute the exterior contact of the lamp or bulb 1. The glass collar 2 forms an upright annular 55 flange 2' projecting sufficiently above ring 7, for the purpose that will be described

later. Within the metallic ring 7 fits a block of electricity insulating paste 9 which projects upwardly and presents in the center of its upper part a recess 10 in which is lodged a small metallic plug 11 forming the interior contact of the lamp or bulb 1 and said block 9 has at its lower portion a button - shaped projection 12 whose head grips with a mass of insulating paste 13 60 which in fluid condition is poured in the small glass funnel 14 through the interior of which pass the electrodes 4 and 5 and which constitutes a support for the glass stud 15 which holds the various portions of 65 filament 16. Said insulating paste 13 fills the upper portion of the small funnel 14 which presents in its inner surface a plurality of projecting glass points 17 distributed along the circle of the small funnel 70 and which serve to grasp with the mass of insulating paste 13 when same is poured in, the lower part of the small funnel being filled with cotton 18. As illustrated in the drawings, the electrode 4 passes through 75 the cotton 18 and mass of insulating paste 13 and is attached to the outer contact 7 and the electrode 5 passes through the cotton 18 and mass of insulating paste 13 and insulating block 9 and is attached to the inner contact 11. 80

The described construction clearly shows that the contacts 7 and 11 of the electric lamp or bulb are perfectly secured to the glass material forming the lamp. 85

This new construction lamp is designed for being used with a non-metallic or electricity non-conducting material socket, such as the socket 19 illustrated in Fig. 4 of the drawing, which has a screw thread 20 at 90 the inner surface of its mouth for threading therein the glass collar 2 of the lamp 1, until the contacts 7 and 11 of lamp 1 respectively engage the contacts 21 and 22 of the contact bearing body 23 which forms a part and occupies the interior of socket 19. Of said two contacts 21 and 22, the outer one 21 is helically shaped so as to bear against the metallic ring 7 of the lamp and the inner one 22 is a button that bears on the central 95 contact 11 of the lamp. The contact bearing body 23 can be of any appropriate construction, it being illustrated as being provided of two small metallic outer plates 24 and 26 lodged in lateral recesses of said body 23 and of which the 24 one is integral 100 with the helical contact 21 and is connected 105

by a fusible wire 25 to the other small plate 26 to which is attached one of the conducting wires 27, the other conducting wire 28 being attached to a metallic central pin 29 5 ending in the contact 22 and which occupies a recess or central cavity in the body 23. Since outer contact 21 of the contact carrying body 23 engages the outer contact 7 of the lamp at a good distance underneath the 10 edge of flange 2' of collar 2 of the lamp, there is no danger that a spark between both contacts may burn the wood of the socket 19 since this socket is entirely protected by the glass of collar 2 of the lamp.

15 Since the lamp is not provided with the common metallic casket and the socket is made out of wood, the construction of both results very cheap.

What I claim is:

20 In electric incandescent lamps having non-metallic sockets, the combination of a glass collar provided with a screw thread adapted to be screwed into a lamp holder, an annular setting on said collar, a metallic 25 ring on said setting, a block of insulating paste within said ring, projections on the

ring embedded in said paste and constituting one of the contacts of the lamp, an upright annular flange on said collar projecting above said ring, said block being provided with a recess in the center of its upper part, a small metallic plug in said recess constituting a second contact, a button shaped projection on the lower part of said block, a glass funnel, insulating paste in the 35 upper part, and a cotton wad in the lower part of said funnel, an electrode passing through said cotton wad and said insulating paste, secured to the ring projections constituting a contact, a second electrode also 40 passing through said cotton wad and insulating paste, secured to said metallic plug, a glass stud secured to said funnel and filaments supported by said stud and connected to said electrodes. 45

In testimony whereof I affix my signature in presence of two witnesses.

VICTORINO MARTINEZ.
